(57) **CLAIM**

The ornamental design for a reinforcing bar, as shown and described.

DESCRIPTION

FIG. 1 is a front elevational view of a reinforcing bar according to a first embodiment of our new design, the rear elevational view being a mirror image of that shown;

FIG. 2 is a left side elevational view thereof, the right side view being a mirror image of that shown;

FIG. 3 is a top plan view thereof, the bottom plan view being a mirror image of that shown;

FIG. 4 is a cross sectional view taken along line 4-4 in FIG. 1; FIG. 5 is a perspective view showing an end portion thereof; FIG. 6 is a front elevational view of a reinforcing bar according to a second embodiment of our new design, the rear elevational view being a mirror image of that shown;

FIG. 7 is a left side elevational view thereof, the right side view being a mirror image of that shown;

FIG. 8 is a top plan view thereof, the bottom plan view being a mirror image of that shown;

FIG. 9 is a cross sectional view taken along line 9-9 in FIG. 6; and,

FIG. 10 is a front elevational view thereof in a position of use. The claimed design as shown in FIGS. 1, 3, 6 and 8 is broken away to indicate that no particular length is claimed.

The broken lines in FIG. 10 is included for the purpose of illustrating environment and forms no part of the claimed design.
